Fig. 5.

A diagram of a stepped rectangular block. The top surface is divided into three horizontal regions: a top section labeled 29, a middle section labeled 25, and a bottom section labeled 26. The vertical faces of the block are labeled 23, 32, 30, and 27. The bottom-most section, labeled 26, is further divided into two horizontal layers: a top layer labeled 30 and a bottom layer labeled 28. The entire block is shaded with diagonal lines.

CASTELLATED NUT.

1,425,591.

Specification of Letters Patent. Patented Aug. 15, 1922.

Application filed May 12, 1919. Serial No. 296,560.

To all whom it may concern:

Be it known that I, FERNANDO OSCAR JAQUES, Jr., a citizen of the United States, residing at Providence, in the county of Providence and State of Rhode Island, have invented a new and useful Improvement in Castellated Nuts, of which the following is a specification.

My invention is an improvement in castellated nuts, reference being had to my application for United States Patent on method of making my improved castellated nuts, filed January 9, 1919, Serial No. 270,420 to which this is a companion application.

In the usual previous construction of castellated nuts, the nuts are machined out of bar metal such as a low grade steel. The nuts with the castellations thereon are only as strong and durable as the bar metal from which they are made and fractures and other faults in the bar metal are reproduced in the nuts, therefore, the nuts can not always be depended on for strength also there is a percentage of seconds thrown out, where the imperfections can be seen. These machined nuts are also comparatively costly to make, they are rough in finish and require polishing for electro plating or for other reasons.

The object of my invention is to improve the construction and reduce the cost of castellated nuts, whereby all of the faults in the old form of machined castellated nuts, as enumerated above, are eliminated and a stronger, more durable, perfect and cheaper castellated nut produced, than has heretofore been done.

My invention consists in the peculiar and novel construction of a castellated nut in which the metal forming the body and castellations is compressed and condensed by the castellated nut being formed up and compressed in dies from a sheet metal blank having radial arms which form the castellations on the nut and in which is a predetermined greater superficial amount of metal than there is in the completed nut, said castellated nut having a strong, durable and uniform condensed structure and finished surface, as will be more fully set forth hereinafter and claimed.

To those skilled in the art to which my invention has reference, I will now describe how my improved castellated nut is made.

Figure 1 is a face view of the metal blank cut out from sheet metal, showing radial

arms on the blank which form the castellations of the completed castellated nut.

Figure 2 is an edge view of the blank.

Figure 3 is a vertical sectional view through dies which cup the blank.

Figure 4 is a vertical sectional view through dies which compress the sheet metal cup, shown in Figure 3, into a hexagonal shaped nut blank.

Figure 5 is a vertical sectional view through dies which punch out the bottom of the nut blank.

Figure 6 is a side view of the lower end of the upper die member, shown in Figure 4, for forming the nut blank.

Figure 7 is a castellated end view of my improved castellated nut, and

Figure 8 is a sectional view through the castellated nut taken on line 8.8 of Figure 7.

In the drawing 9 indicates a sheet metal blank having a flat body portion 10 from which extend flat radial arms 11.11. 12 a lower fixed die member having a cylindrical cavity 13 and a bottom hole 14. 15 80 an upper die member shaped to fit in the cavity 13 and having a lower end 16, the lower and upper die members 12 and 15 being shaped to form the blank 9 into a cylindrical cup 17 having a closed bottom 18 and 85 an open castellated end, as shown in Figure 3, said cup 17 having a greater depth than the height of the completed castellated nut. 19 a lower die member having a cavity 20 shaped to form the outside of the nut blank 90 and a closed bottom 21. 22 an upper die member shaped to fit in the cavity 20 and having the portion 23 shaped to form the castellations on the nut out of the arms on the blank, and the end 24 shaped to form 95 the inside of the nut blank, as shown in Figures 4 and 6. 25 a compressed nut blank having the closed bottom 18 and open castellated end, as shown in Figure 4. 26 a lower die member having a cavity 27 shaped to receive the nut blank 25, and a central bottom hole 28. 29 an upper die member having the punch end 30 for punching out the bottom 18 of the nut blank 25, as shown in Figure 5, and 31 the completed castellated nut having 100 105 the castellations 32,32 and the central screw-threaded hole 33 as shown in Figures 7 and 8.

A blank 9 having a flat body 10 and radial arms 11.11 is cut out of sheet metal by 110

suitable dies. The blank is then placed in suitable cupping dies and cupped, forming a comparatively deep cylindrical cup having an open castellated end, formed from the 5 arms on the blank. The cup blank is then placed in suitable nut blank forming dies and the cup compressed into a castellated nut blank having a closed end. The nut blank is then placed in suitable punching 10 dies and the closed bottom of the nut blank punched out. The nut blank is then internally screw-threaded, thereby completing the castellated nut.

My improved castellated nut made from a 15 sheet metal blank compressed into the castel-

lated nut has a condensed uniform structure, it is stronger and more durable and having a hard smooth outer surface, it will wear longer and is rust resisting, and this hard smooth surface covers the entire outer surface of the nut and its castellation. 20

Having thus described my invention I claim as new:—

A nut blank having castellations and formed of sheet metal compressed and having a central hole and a web extending 25 across the central hole.

In testimony whereof, I have signed my name to this specification.

FERNANDO OSCAR JAQUES, JR.
